UNITED STATES PATENT OFFICE.

GEORGE DILLER, OF MITCHELL, SOUTH DAKOTA.

WATER SKI.

Application filed February 1, 1926. Serial No. 85,258.

This invention relates to certain new and useful improvements in water ski, and the primary object thereof is to provide a ski which rides more nearly on the surface of the water, which is not susceptible to easy tipping, and which permits the user to easily make turns without loss of balance.

A further object of the invention is to provide a ski which has improved water wings for assuring return of same to normal position prior to commencement of the back stroke.

In the drawings:—

Fig. 1 is a side elevation of the invention;

Fig. 2 is a top plan view, and

Fig. 3 is an enlarged section on line 3—3 of Fig. 1.

In proceeding in accordance with the present invention, a pontoon is employed having a foot engaging top 1, sides 2 depending from the top, and a bottom 3, these parts being connected to form an air sealed chamber. The front ends of the sides 2 curve upwardly at 4' toward the toe part 25 of the ski whereby the toe part is raised.

The sides 2 are formed with extensions 4 that project below the bottom 3 and constitute a double keel. The forward ends of the keel members 4 are also curved upwardly and terminate adjacent the bottom. The top 1 has a heel support 5 at its rear equipped with a securing strap 6, while the forward part of the top is equipped with a securing strap 7 to engage the toe portion of the foot.

The keel members 4 receive therebetween the resistance or water engaging wings 8, which wings are supported by and from the keel members by means of transverse pins 9. The wings may be formed of sheet metal and have curled upper ends 10 receiving the pins 9 and flange sides 11, the flanges being tapered and having their widest ends engageable with the pontoon bottom 3 so as to space the bodies of the wings from the pontoon bottom upon the forward stroke of the ski, thus assuring the wings freely and promptly gravitating to the position of Fig. 1, upon the end of the forward stroke. The flanges thus act to prevent any possible sticking or adhering of the wings to the pontoon bottom. Stop pins 12 carried by one of the keel-members are employed to arrest forward movement of the wings.

From the foregoing it will be seen that a double keel is provided which prevents

tipping, and that the wings are carried by the keel and are held out of area or surface contact with the bottom of the pontoon, thus assuring proper functioning of each 60 and all thereof. The two keels act to prevent loss of balance in turning and by the upwardly tapered construction of the keels and pontoon sides the ski rides higher on the surface of the water and thus easily 65 thereon.

What is claimed is:—

1. In a water ski, a pontoon having a top, bottom and sides, the sides being extended below the bottom to form a pair of spaced 70 keel members, said sides being curved upwardly and forwardly from their lower edges, a series of wings having tapered side flanges disposed between the keel members and having their widest parts engageable 75 with the pontoon bottom, pins on which the wings are pivotally mounted connected to the keel-members, and stops carried by one of the keel members to engage and arrest forward movement of the wings. 80

2. In a water ski, a pontoon having a top, bottom and sides, the sides being extended below the bottom to form a pair of spaced keel members, said sides being curved upwardly and forwardly from their lower edges, a series of wings pivoted between the keel-members, and spaced below the pontoon bottom, and means to arrest forward movement of the wings. 85

3. In a water ski, a pontoon having a 90 bottom and sides the fronts of the sides and the front of the bottom being curved upwardly and forwardly, the sides being extended below said bottom to form a pair of spaced keel members, the fronts of said 95 extensions of the sides being curved upwardly and forwardly and substantially merging into the first named curved parts of the sides and bottom and water resisting means between the keel members. 100

4. In a water ski, a pontoon, wings pivotally carried by the pontoon and projecting below the bottom thereof, side flanges on the wings engageable at their side edges with the pontoon bottom to hold the bodies of the wings spaced from the bottom, and means to arrest forward movement of the wings. 105

5. In a water ski, a pontoon, wings pivotally carried by the pontoon and projecting below the bottom thereof, means carried by each wing to engage the pontoon body to 110

hold the bodies of the wings spaced from the bottom, and means to arrest forward movement of the wings.

6. In a water ski, a pontoon, wings pivotally carried by the pontoon and projecting below the bottom thereof, means carried by each wing to engage the pontoon body to hold the bodies of the wings spaced from the bottom, and a stop for each wing to arrest forward movement thereof.

7. In a water ski, a pontoon, spaced keel members on the bottom of the pontoon, and wings pivotally carried by the keel-members and spaced from the pontoon bottom and having side flanges formed to have their side edges engage the pontoon bottom, to prevent contact of the bodies of the wings with the pontoon bottom.

In testimony whereof I affix my signature.

GEORGE DILLER.
